WILLIAM E. JENKINS, OF AUBURN, NEW YORK.

Letters Patent No. 93,092, dated July 27, 1869.

IMPROVEMENT IN OIL-CANS.

The Schedule referred to in these Letters Patent and making part of the same.

To all whom it may concern:

Be it known that I, WILLIAM E. JENKINS, of Auburn, in the county of Cayuga, and State of New York, have invented certain new and useful Improvements in Oil-Cans; and I do hereby declare that the following is a full, clear, and exact description thereof, reference being had to the accompanying drawings, and to the letters of reference marked thereon, which form a part of this specification, and in which is represented a longitudinal section of my oil-can.

My invention relates to improvements in oil-cans; and to this end,

It consists in the employment, in an ordinary oil-can, of a tube provided with a spiral spring, in combination with a curved rod attached to the cork, the object of which will hereinafter be fully set forth.

To enable others skilled in the art to which my invention appertains, to make and use the same, I will now describe its construction and operation.

In the accompanying drawing—

A represents the oil-can.

B is a tube, inserted in the top of can, and provided with spiral spring a.

To spring a is attached the rod b, curved at its upper end, and entering the cork d, as seen in the drawing.

D represents the can-spout.

By this arrangement, it will be seen that the cork is always kept air-tight in the can. All that it is necessary to do, in order to pour out the oil, is to press up the rod b, which removes the cork sufficiently to allow the oil to pass out of the spout.

Having thus described my invention,

What I claim, and desire to secure by Letters Patent, is—

An oil-can, consisting of top A, tube B, spiral spring a, rod b, and cork d, all combined, arranged, and operating substantially in the manner and for the purpose described.

In testimony that I claim the foregoing as my own, I affix my signature, in presence of two witnesses.

WILLIAM E. JENKINS.
